(57) **CLAIM**

The ornamental design for a heat-dissipating bracket, as shown and described.

DESCRIPTION

FIG. 1 is a perspective view of a heat-dissipating bracket showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof showing the heat-dissipating bracket in the closed status; and,

FIG. 10 is another perspective view thereof showing the heat-dissipating bracket in the closed status.

The broken lines illustrate portions of the heat-dissipating bracket that form no part of the claimed design.
